United States Patent

Des. 237,224
Patented Oct. 21, 1975

237,224

SHOE

Joseph P. Famolare, Jr., Florence, Italy, assignor to Famolare, Inc., New York, N.Y.

Filed Mar. 29, 1973, Ser. No. 345,902

Term of patent 14 years

Int. Cl. D2—04

U.S. Cl. D2—313

FIG. 1 is a front perspective view of a shoe showing my new design;

FIG. 2 is a rear elevational view thereof; and

FIG. 3 is a side elevational view thereof.

I claim:

The ornamental design for a shoe, substantially as shown and described.
